WARREN A. SMITH, OF GENEVA, ILLINOIS.

CHAPLET-FORMING MACHINE.

Application filed March 25, 1925. Serial No. 18,182.

This invention is, generically, a metal bending machine. It is especially designed for use in forming metal chaplets for use by foundrymen as a means of supporting or 5 maintaining the proper distance between parts of a mold in which a casting is to be made. The invention is especially designed for use on chaplets well known in the art, made of perforated metal which are bent 10 into more or less rectangular form and frequently provided with an integral member separating the two longest sides of the rectangle at approximately the middle of the chaplet.

15 The principal object of the invention is to construct a machine for this work in which the use of the ordinary expensive dies is dispensed with, in which chaplets of different desired sizes can be readily formed 20 on one and the same machine by merely substituting a different horn or block around which the chaplet is formed by the machine, and changing one or two other minor parts which can be much more easily accomplished 25 than in the case of machines of the prior art.

The invention consists in a machine capable of attaining the foregoing and other objects hereafter set forth; which can be 30 comparatively easily and cheaply made; which is very highly efficient in operation and is not readily liable to get out of order.

More particularly the invention consists 35 in numerous features and details of construction which will be hereafter more fully set forth in the specification and claims.

Referring to the drawings in which like numerals designate the same parts throughout the several views:

40 Figure 1 shows seven different, commercial forms of chaplet which can be made by this machine.

Figure 2 is a front elevation of the machine showing the end into which the raw 45 material to be formed into chaplets is fed.

Figure 3 is a side view, taken from the right of Figure 2.

Figure 4 is a plan view of Figure 3.

Figure 5 is a central, side elevation, taken 50 on the line 5—5 Figure 4.

Figure 6 is a plan view of the horn on which the chaplets are formed, together with its supporting bracket, removed from the rest of the machine.

55 Figure 7 is a perspective view of the essen-

tial part of the horn taken from the lower left hand corner of Figure 6.

Figure 8 is a bottom perspective view of the horn of Figure 7.

Figure 9 is a perspective view showing the feed bar of the machine loaded with material from which a chaplet is made, showing the progressive steps in the formation of a chaplet as it is carried by this feed bar through the machine.

Figure 10 is a sectional, end view on approximately the line 10—10 of Figure 5.

Figures 11, 12, 13 and 14 are detail views of essential operating parts, taken at lines 11, 12, 13 and 14 of Figure 5, showing the 70 first, second, third and fourth steps in the formation of the chaplet, Figure 10 showing the fifth step.

The mechanism of this invention is carried within a suitable supporting frame 75 which may vary materially in shape without departing from this invention. The particular frame here used consists of two parallel, side frame members 16 and 18, united at one end by the plate 20 detachably secured 80 in place by any suitable means as, for instance, bolts 22 and spaced apart near the middle of the machine by a partition 24 entered by bolts or screws 26 passing through the side frame members. The frame parts 85 heretofore described are sustained on conventional legs 28 rising from the floor or other suitable support.

Suitably journaled in the frame is a transverse, main driving shaft 30 equipped at 90 one end with the conventional pulley 32 or the like to which power from an outside source, not entering into this invention, is applied in any suitable conventional manner.

Rigid upon drive shaft 30 in proximity 95 to the longitudinal middle of the machine is a miter beveled gear 34 meshing with beveled gear 36 on the end of a shaft 38 at right angles to shaft 30. Shaft 38 is conventionally journaled in a bearing 40 formed in 100 partition 24 and in a bearing 42 formed on the lower edge of plate 20.

A very important part of the machine is the feed bar mechanism shown in perspective in Figure 9, the same consisting of a long bar 44 and a shorter bar 46, parallel thereto, the two being rigidly secured together in a movable carrier block 48. The two bars 44 and 46 are equipped with work feeding teeth 50, those on the two bars be- 110

ing opposite to each other so that a work blank 52 lying across them will be at right angles to the longitudinal planes of the bars.

Bars 44 and 46 are, as shown and described, spaced apart a substantial distance so that they can be located on opposite sides of a work supporting table 54 stationarily secured in place on the upper end of partition 24 by any suitable means, as, for instance, the screw 56. The fit of the parts is such that, as hereafter described, the work bars 44 and 46 may be moved vertically downward past the sides of this table 54 to a point where the top edges of the teeth 50 are below the upper surface of the table, this so that the work bars may be reciprocated under work blanks 52 resting on the table a sufficient distance so that the teeth will feed the work blanks along the table in a ratchet-like motion.

The carrier block 48 is mounted for the foregoing purpose below table 54, as clearly shown in Figure 5. The block 48 is, itself, horizontally reciprocal along the upper shelf 25 of a right angle bracket 58 whose vertical arm 58^a is vertically reciprocal in guides 60, formed on one side of partition wall 24. Vertical motion is given to this bracket in these guides through an eccentric cam 62 on shaft 38 contacting a roller 64 journaled in a laterally extending arm 66 on the lower end of bracket 58. The weight of the bracket and associated parts is sufficient to hold roller 64 in engagement with cam 62 in all positions of the parts. Horizontal motion along the top of bracket 58 is imparted to work carrier block 48 through the agency of a connecting rod 68, pivotally connected to a lever 70 keyed to a shaft 72 journaled in the frame. One end of this shaft 72 carries a crank 74 operatively connected through a conventional adjustment mechanism 76 with an eccentric 78 on main shaft 30. The two eccentrics 78 and 62 are so designed and adjusted that as the two main shafts 30 and 38 rotate, the work holder block 48 is given the desired ratchet motion described to carry work blanks 52 placed upon the table 54 from left to right through the machine, as viewed in Figure 5, between the successive positions shown upon the work blank in Figure 9.

One method of applying work blanks 52 is to have them cut outside the machine to the size shown in Figure 9, and manually apply them one at a time at the left hand end of the feeding device of Figure 9. The machine of the drawings, however, contemplates feeding a continuous sheet of workable material 80 into the machine from the top, as shown in Figure 5, severing it in the machine into separate work blanks, and dropping such blanks one at a time into place on the work carrier. One method of accomplishing this result shown in the draw-

ings comprises a stationary shear member 82 and a horizontally reciprocal shear member 84, operatively associated together to sever portions of workable material at the juncture of these shear members and drop 70 the severed pieces into a carrier 86 which deposits the sheared piece of workable material on the table 54 in reach of the feeding bars 44-46. In detail, the movable shear 84 is rigidly secured in a horizontally reciprocal cross-head 88 connected at its opposite ends by parallel links 90 to a yoke 92 pivoted on sleeves, not shown, surrounding shaft 94 hereafter referred to. Pivotally connected to a lug 96 on this yoke 92 is a parallel 80 bar connecting rod 98 pivoted at its lower end to a short arm 100 of a bell crank journaled on shaft 72, the longer arm 102 of the bell crank carrying a roller 104 held against a cam 106 on shaft 30 by any conventional 85 spring mechanism not shown. The parts just described are so shaped and proportioned that movable shear blade 84 is reciprocated across stationary blade 82 at the proper time to sever work blanks from workable material 80 as they are required by the work carrier mechanism 44-46 in the proper operation of the machine.

The carrier member 86 heretofore referred to is rigidly mounted upon shaft 94. Rigid on shaft 94 is a crank 108 pivotally engaging a connecting rod 110 attached at its opposite end to the upper end of a lever 112 loosely journaled at its middle on shaft 72, the lower end of this lever carrying a cam roller 114 traveling in the groove track 116 of a cam wheel 118 on shaft 30. The upper edge of carrier 86 in the position shown in Figure 5 is provided with a work blank holding notch 120 adapted to, as shown, receive blanks severed from material 80. The depth of this notch 120 may be varied by an adjusting screw 122 to accommodate blanks of different sizes to be treated by the machine. The cam track 116 is so shaped that on a complete revolution of shaft 30, carrier 86 will be rocked from the position of Figure 5 in a clockwise direction sufficiently to allow a work blank in the notch 120 to slip out of said notch onto table 54 in engagement with the feed bar mechanism 44-46 and the cam is so located with reference to the other cams heretofore referred to that this dropping of the feed blank occurs at exactly the proper time to cooperate with other operations of the machine.

When a blank 52 has been deposited either by hand or by the carrier 86 on the table 54 at the left hand end of the carrier 44-46 and the machine is operating, the movement of the carrier block 48 causes the blank to travel to the right through the machine as viewed in Figure 5 along the top of the table 54 between guides 60, adjustable to and from the work by bolt and slot connec-

tions 55 to the frame, until it reaches a position in the plane of the line 11 of Figure 5, viz: the first forming station. In this position shown in Figure 11, the blank 52 is first positioned or gauged by gauging steel 124 on the under side of horn 126. It is next rigidly clamped to the under side of the horn by the end of clamp plate 128. This clamp plate 128 extends as shown in Figure 5 for a substantial distance longitudinally of the machine and intermittently holds the work at different bending stations hereafter described. This clamp plate is operated by a vertically reciprocal cross-head 130 carrying at its lower end a roller 132 traveling on a cam 134 on shaft 38, the cam being so proportioned that the clamp will be applied to the work at proper intervals as it is carried by the mechanism 44-46 from left to right through the machine as shown in Figure 5.

Having been clamped in the position of Figure 11, it is engaged by the first forming slide or tool 136, vertically reciprocal through the agency of a roller 138 which it carries, traveling on cam 140 on shaft 38 and always held in contact with the cam by springs not shown. The working part of this tool 136 consists of two parallel bending tools 142 and 144, operating on opposite sides of clamp 128 and the adjacent part of feed bar 44 to give the adjacent portion of the work blank 52 a U-shaped bend around an end portion 145 of the horn 126. The bending tool 142 in this operation thus makes what is ultimately the bridge 146 of the finished products, shown in Figure 1. The tool 144 makes an end 148 of said finished product. The upward reciprocation of the tool 136 and its ultimate return to lowered position leaves the product in the position shown in Fig. 12 in which position the clamp 128, having been released, it is moved by the carrier device 44-46 along the horn from the position of line 11 to the position of line 12 of Fig. 5. In doing this, it travels through one intermediate position of the carrier 44-46 in which no bending is done on the work. In passing through this idle station just described, the bridge 146 of the work blank enters at 150 a slot 152 formed in horn 126. On the underside of the horn, the lower edge of the part bordering this groove is cut away in the notched recess 154 for the reception of feeder teeth 50.

When the particular work blank being handled reaches the position of Figure 12 with its bridge part 146 in the slot 152 in the horn 126, it is momentarily clamped by clamping jaw 128 which at this point carries a projecting plate 156 which covers that portion of the work which was formed at the first station and by the mechanism shown in Figure 11. The work blank is now bent in a counter-clockwise direction over the top of horn 126. This bending action is

produced by a right to left ironing or scraping movement by a forming steel 158 carried on lever 160 pivotally mounted at 162 on the upper end of a lever 164 journaled on a suitable supporting shaft or bar 166, there being on the lower end of the lever 164 a cam roller 168 traveling in a cam track 170 in a cam wheel 172 rigid on shaft 38. The end of lever 160 opposite to forming member 158 is provided with a roller 174 traveling on a cam 176 carried by bracket 178, adjustable by means of a bolt 179 on frame 16. The cams 170 and 176 are so shaped and correlated that forming bar 158 sweeps the engaged portion of the work blank over onto the top of the horn 126 thus forming portion 180 of the finished product. This may be curved or straight, depending upon the form of the upper surface of the horn 126 at this point. Further rotation of shaft 38 and cam 170 returns the parts just described to the position of Figure 12 in which position the clamp on the work is released.

The feeding mechanism 44-46-48 now operates to move the work along into the position shown in Figure 13, under rigid, stationary guide block 182, serving the function of preventing the outer or right hand end of the horn 126 from springing up away from the feeding mechanism 44-46 and acting as an upper jaw in which section 180 of the finished product is clamped by plate 128. As soon as the section 180 of the work reaches the position of Figure 13, clamp 128 acts to hold it against jaw 182 whereupon the next portion 184 of the finished product is bent downward over the horn by a downward, wiping movement of forming steel 186. The mechanism for causing this steel 186 to perform this desired function consists in a lever 188 having at its opposite end a U-shaped notch 190 by means of which it slides over a non-circular rotatable stud 192. This U-notch sliding connection with this stud allows the steel 186 to be reciprocatingly moved so as to cause it to follow either a straight line or any predetermined curved line desired in its downward sweep, bending the part 184 of the work. Lever 188 is pivoted near its middle by a suitable pin connection 194 to a vertically reciprocal connecting rod 196 having its upper end equipped with a roller 198 traveling over a stationary cam face 200 and urged into contact therewith by a spring not shown. The lower end of connecting rod 196 is pivoted at 202 to the short arm 204 of a bell crank pivoted at 206 whose longer arm 208 carries a cam roller 210 traveling in a cam slot 212 in a rotatable cam wheel 214 on shaft 38. Cam track 212 and the cam 200 are so shaped as to, in a complete rotation of the shaft 38, cause a downward, wiping movement of steel 186 in the path desired to properly

form the work section 184 and to ultimately return all of the parts except the work to the position shown in Figure 13 and to there release the clamp 128.

5 The horn 126 at the point illustrated in Figure 13 is supported on its left hand side as viewed in that figure by a small block 216 as shown, the same being rigidly secured by any suitable means to clamp 128.

10 The operation carried on by the mechanism of Figure 13 having been completed, the feeding device 44-46 carries the work into the position shown in Figure 14 wherein the final work section 216 is produced by 15 a left to right swinging action of forming steel 218 carried on a lever 220 pivoted at 222 on the upper end of a lever 224 pivoted on pin 206 heretofore referred to, the lower end of this lever 224 carrying a roller 226 20 traveling in a cam track 228 in cam wheel 230 on shaft 38. The end of lever 220 away from steel 218 carries a roller 232 traveling on the underside of a stationary cam 234. Cams 234 and 228 are so shaped that on a 25 complete revolution of shaft 38, steel 218 travels from left to right as shown in Figure 14 across the under side of the horn, thus bending final section 216 of the work to final position and thereafter returning the 30 steel 218 to the initial position shown in the figure. This completes the bending operations required to form the finished product or products shown in Figure 1. At this point, the finished product has reached the 35 ends of the finger bars 44 and it is no longer moved by that part. It is, however, moved by the next formed chaplet coming into the position of Figure 14 out of that position to a position just at the right of section line 40 10 of Figure 5 wherein it is directly over squeeze block 236—the lower jaw member of a clamp whose upper jaw is the right hand end of member 182, heretofore described. Block 236 is detachably secured by 45 any suitable means, as, for instance, screws 238, to a lever 240 pivoted at 242 to a bracket 244 on the side of the machine. This bracket is adjustable vertically of the 50 machine through a conventional pin and slot connection 246.

The non-pivoted end of lever 240, and squeeze block 236 carried by it, is vertically reciprocal through the agency of a double link 248 pivotally connected at 250 to the 55 shorter arm 252 of a bell crank pivoted at 254, the longer arm 256 of the bell crank carrying a roller 258 traveling on a cam 260 on shaft 38. Roller 258 is held on cam 260 by a conventional spring not shown. The 60 construction is such that at each complete revolution of shaft 38, squeeze block 236 is moved upward with sufficient power to clamp the particular section of the finished product which is above it against member 182 65 and thus set the previously bent parts in the

final desired position determined by the end of the horn 126 which is still within it. In each complete revolution of the shaft 38, the squeeze block 236 is withdrawn from the previously compressed finished product 70 sufficiently so that it can under the urging of other chaplets behind it be forced out into the chute 262 down which the finished product drops into any suitable receptacle provided for the purpose. 75

Guide block 182 is made up of two parts: a forming plate 182, which is shaped to correspond to the particular chaplet which the machine is at a particular time engaged in making, this plate being detachably securable by any suitable means, as the screws 264 to the main block 182^a which is in the particular case here illustrated a casting adjustably secured by pin and slot connections 266 to an overhanging arm bracket 268 suitably secured to the frame of the machine. Member 182^a is vertically adjustably positioned by set screws 270 in the bracket 268. 80

85 The horn 126 is detachably secured to a bracket 272 by any suitable means as, for instance, the cap screws 274. This bracket, itself, is detachably secured in position on the frame 18 by cap screws 276. The machine is equipped with horns 126 of different shapes corresponding to the finished product which is to be produced and on starting to produce a given product, the horn for that product is inserted in the machine, by methods which are entirely obvious from the foregoing description of the parts. 90

95 In the complete operation of the machine, material 80 is fed downward as shown in Figure 5, severed and delivered onto the feed mechanism 44-46 which carries it step by step from left to right as viewed in Figure 5 through the successive positions in the machine during which progress it is bent successively as shown in Figures 11, 12, 13 and 14 and is finally squeezed to finished form, after which it is passed out of chute 262, all as fully heretofore set forth. 100

105 Having thus described my invention, what I claim as new and desire to secure by Letters Patent is:

110 1. In a chaplet machine, a stationary horn about which a chaplet having a bridge may be wrapped having a longitudinal slot through which the bridge of the chaplet may pass, mechanism forming a complete chaplet about the horn with its bridge member in said slot, and means finally squeezing the chaplet into final position on the horn. 115

120 2. In a chaplet machine, a stationary horn about which a chaplet having a bridge may be wrapped having a longitudinal slot through which the bridge of the chaplet may pass, mechanism forming a complete chaplet about the horn with its bridge member in said slot, and means finally delivering the 125 chaplet from the end of the horn. 130

3. In a chaplet machine, a stationary horn about which a chaplet having a bridge may be wrapped having a longitudinal slot through which the bridge of the chaplet may pass, mechanism forming a complete chaplet about the horn with its bridge member in said slot, means finally squeezing the chaplet into final position on the horn, and means finally delivering the chaplet from the end of the horn.
4. In a chaplet machine, a generally rectangular stationary horn about which a chaplet having a bridge may be wrapped having a longitudinal slot through which the bridge of the chaplet may pass, and mechanism forming a complete chaplet about the horn with its bridge member in said slot by bending an end of a metal strip into said slot and bending successive parts of the strip against successive sides of the horn.
5. In a chaplet machine, a generally rectangular stationary horn about which a chaplet having a bridge may be wrapped having a longitudinal slot through which the bridge of the chaplet may pass, mechanism forming a complete chaplet about the horn with its bridge member in said slot, by bending an end of a metal strip into said slot and bending successive parts of the strip against successive sides of the horn, and means finally squeezing the chaplet to final position on the horn.
6. In a chaplet machine, a generally rectangular stationary horn about which a chaplet having a bridge may be wrapped, having a longitudinal slot through which the bridge of the chaplet may pass, mechanism forming a complete chaplet about the horn with its bridge member in said slot by bending an end of a metal strip into said slot and bending successive parts of the strip against successive sides of the horn, and means finally delivering the chaplet from the end of the horn.
7. In a chaplet machine, a generally rectangular stationary horn about which a chaplet having a bridge may be wrapped having a longitudinal slot through which the bridge of the chaplet may pass, mechanism forming a complete chaplet about the horn with its bridge member in said slot by bending an end of a metal strip into said slot and bending successive parts of the strip against successive sides of the horn, means finally squeezing the chaplet to final position on the horn, and means finally delivering the chaplet from the end of the horn.
8. In a chaplet making machine, an elongated stationary horn shaped in cross section for forming a finished chaplet, means feeding an elongated blank of metal step by step sideways along the horn, means at each step in the travel of the blank clamping a portion of the blank to the adjacent side of the horn, bending the next adjacent portion of the blank into engagement with the next adjacent side portion of the horn.
9. In a chaplet making machine, an elongated horn shaped in cross section for forming a finished chaplet, means feeding an elongated blank of metal step by step sideways along the horn, means at each step in the travel of the blank clamping a portion of the blank to the adjacent side of the horn, 75 means at each clamped position bending the next adjacent portion of the blank into engagement with the next adjacent side portion of the horn, and means finally squeezing the chaplet into final position on the horn.
10. In a chaplet making machine, an elongated stationary horn shaped in cross section for forming a finished chaplet, means feeding an elongated blank of metal step by step sideways along the horn, means at each step in the travel of the blank clamping a portion of the blank to the adjacent side of the horn, means at each clamped position bending the next adjacent portion of the blank into engagement with the next adjacent side portion of the horn, and means finally squeezing the chaplet into final position on the horn.
11. In chaplet making machine, an elongated horn shaped in cross section for forming a finished chaplet, means feeding an elongated blank of metal step by step sideways along the horn, means at each step in the travel of the blank clamping a portion of the blank to the adjacent side of the horn, means at each clamped position bending the next adjacent portion of the blank into engagement with the next adjacent side portion of the horn, and means finally delivering the chaplet from the end of the horn.
12. In a machine of the class described, a horn for forming chaplets made up of two parallel, long members, about which the chaplet can be bent into form, there being between the members a slot for retaining and controlling the passage of a portion of a chaplet, said slot being widened at one point between the members to permit bending into it the part of the chaplet which is to travel in the slot.
13. In a machine of the class described, a horn for forming chaplets made up of two parallel, long members, about which the chaplet can be bent into form, there being between the members a slot for retaining and controlling the passage of a portion of a chaplet, said slot being widened at one point between the members to permit bending into it the part of the chaplet which is to travel in the slot, one of said members adjacent to said widened part of the slot being of such a shape as to give a part of the material

of the chaplet a U-shaped formation, one of whose arms is the chaplet part bent into the slot.

14. In a chaplet making machine, an elongated horn shaped in cross section for forming a finished chaplet, means detachably securing a chaplet blank to one side of the horn, means moving across the longitudinal axis of the horn bending the material of the blank onto a different side of the horn, such a bending mechanism for each side of the horn, means temporarily releasing the securing means, means for feeding a chaplet blank along the horn to the successive bending mechanisms, and means operating the bending mechanisms.

15. In a chaplet making machine, an elongated horn shaped in cross section for forming a finished chaplet, means detachably securing a chaplet blank to one side of the horn, means moving across the longitudinal axis of the horn bending the material of the blank onto a different side of the horn, such a bending mechanism for each side of the horn, means temporarily releasing the securing means, means for feeding a chaplet blank along the horn to the successive bending mechanisms, and means operating the bending mechanisms, said bending mechanisms being so located along the horn as to bend the chaplet blank over successive sides of the horn one after the other.

16. In a chaplet making machine, an elongated horn shaped in cross section for forming a finished chaplet, means detachably securing a chaplet blank to one side of the horn, means moving across the longitudinal axis of the horn bending the material of the blank onto a different side of the horn, such a bending mechanism for each side of the horn, means temporarily releasing the securing means, means for feeding a chaplet blank along the horn to the successive bending mechanisms, and means operating all of the bending mechanisms in timed relation.

17. In a chaplet making machine, an elongated horn shaped in cross section for forming a finished chaplet, means detachably securing a chaplet blank to one side of the horn, means moving across the longitudinal axis of the horn bending the material of the blank onto a different side of the horn, such a bending mechanism for each side of the horn, means temporarily releasing the securing means, means for feeding a chaplet blank along the horn to the successive bending mechanisms, and means operating all of the bending mechanisms in timed relation, said bending mechanisms being so located along the horn as to bend the chaplet blank over successive sides of the horn one after the other.

18. In a chaplet making machine, an elongated horn shaped in cross section for forming a finished chaplet, means detachably

securing a chaplet blank to one side of the horn, means moving across the longitudinal axis of the horn bending the material of the blank onto a different side of the horn, and means giving the chaplet a squeeze after it leaves the last bending mechanism for the purposes set forth.

19. In a chaplet making machine, an elongated horn shaped in cross section for forming a finished chaplet, means detachably securing a chaplet blank to one side of the horn, means moving across the longitudinal axis of the horn bending the material of the blank onto a different side of the horn, such a bending mechanism for each side of the horn, means temporarily releasing the securing means, means for feeding a chaplet blank along the horn to the successive bending mechanisms, means operating the bending mechanisms, and means giving the chaplet a squeeze after it leaves the last bending mechanism for the purposes set forth.

20. In a chaplet making machine, an elongated horn shaped in cross section for forming a finished chaplet, means detachably securing a chaplet blank to one side of the horn, means moving across the longitudinal axis of the horn bending the material of the blank onto a different side of the horn, such a bending mechanism for each side of the horn, means temporarily releasing the securing means, means for feeding a chaplet blank along the horn to the successive bending mechanisms, means operating the bending mechanisms, said bending mechanisms being so located along the horn as to bend the chaplet blank over successive sides of the horn one after the other, and means giving the chaplet a squeeze after it leaves the last bending mechanism for the purposes set forth.

21. In a chaplet making machine, an elongated horn shaped in cross section for forming a finished chaplet, means detachably securing a chaplet blank to one side of the horn, means moving across the longitudinal axis of the horn bending the material of the blank onto a different side of the horn, such a bending mechanism for each side of the horn, means temporarily releasing the securing means, means for feeding a chaplet blank along the horn to the successive bending mechanisms, means operating all of the bending mechanisms in timed relation, and means giving the chaplet a squeeze after it leaves the last bending mechanism for the purposes set forth.

22. In a chaplet making machine, an elongated horn shaped in cross section for forming a finished chaplet, means detachably securing a chaplet blank to one side of the horn, means moving across the longitudinal axis of the horn bending the material of the blank onto a different side of the horn, such a bending mechanism for each side

- of the horn, means temporarily releasing the securing means, means for feeding a chaplet blank along the horn to the successive bending mechanisms, means operating all of the 5 bending mechanisms in timed relation, said bending mechanisms being so located along the horn as to bend the chaplet blank over successive sides of the horn one after the other, and means giving the chaplet a squeeze 10 after it leaves the last bending mechanism for the purposes set forth.
23. In a chaplet machine, feeding means transporting chaplet blanks into the machine, means delivering sheet metal into the 15 machine at an angle to the path of movement of the feeding means, means severing a chaplet blank from the sheet, and a rocking carrier depositing the blank on the transporting means.
- 20 24. In a chaplet machine, a reciprocating step by step feeding means transporting chaplet blanks into the machine, means delivering sheet metal into the machine, means severing a chaplet blank from the 25 sheet, means depositing the blank on the transporting means, and a single power means operating all said parts in timed relation to deliver one chaplet blank to the feeding means at each reciprocation.
- 20 25. In a chaplet machine, a reciprocating step by step feeding means transporting chaplet blanks into the machine, means delivering sheet metal into the machine at an angle to the path of movement of the transporting means, means severing a chaplet blank from the sheet, means depositing the blank on the transporting means, and a single power means operating all said parts 35

in timed relation to deliver one chaplet blank to the feeding means at each reciprocation. 40

26. In a chaplet machine, a reciprocating step by step feeding means transporting chaplet blanks into the machine, means delivering sheet metal into the machine at an angle to the path of movement of the transporting means, means severing a chaplet blank from the sheet, a rocking carrier depositing the blank on the transporting means, and a single power means operating all said parts in timed relation to deliver 50 one chaplet blank to the feeding means at each reciprocation.

27. In combination with a horn over which a chaplet blank is to be bent, a wiping tool and means carrying said wiping tool over the horn surface, the same consisting of a lever carrying the tool at one end, a cam controlled at the other end of said lever, a second rockable lever carrying at one end the first lever, a controlling cam for the second lever, and driving means for the last mentioned cam. 55

28. In combination with a horn over which a chaplet blank is to be bent, a wiping tool and means carrying said wiping tool over the horn surface, the same consisting of a lever carrying the tool at one end, a stationary cam controlling the other end of said lever, a second rockable lever carrying at one end the first lever, a cam controlling the second lever, and driving means for the last mentioned cam. 60 70

In witness whereof, I have hereunto subscribed my name.

WARREN A. SMITH.
